BOOTJACK

Maurice M. Cairns, Roseburg, Oreg., assignor to North Pacific Products, Inc., Bend, Oreg.

Filed Feb. 9, 1971, Ser. No. 113,990

Term of patent 14 years

Int. Cl. D3—99

U.S. Cl. D86—10 D

FIG. 1

FIG. 4

FIG. 1 is a top perspective view of a bootjack showing my new design;

FIG. 2 is a side elevation view thereof, the side opposite being a mirror image;

FIG. 3 is an end elevation view as seen from the left of FIG. 2; and

FIG. 4 is a bottom plan view thereof.

I claim:

The ornamental design for a bootjack, as shown and described.
